[57] CLAIM

An ornamental design for a chandelier, as shown and described.

DESCRIPTION

FIG. 1 is a front elevation view of the chandelier showing my new design.

FIG. 2 is a right side elevation view of the chandelier of FIG. 1.

FIG. 3 is a left side elevation view of the chandelier of FIG. 1.

FIG. 4 is a rear elevation view of the chandelier of FIG. 1. FIG. 5 is a top plan view of the chandelier of FIG. 1; FIG. 6 is a bottom plan view of the chandelier of FIG. 1; and, FIG. 7 is a front elevation view of a second embodiment of the chandelier of FIG. 1.

Features shown in broken lines are shown for environment only and do not form a part of the design claimed.

The appearance of the design of the embodiment of FIG. 7 repeats every 120° about the vertical axis of the chandelier. In top plan view, elements of the embodiment of FIG. 7 appear the same as like elements in the top plan view of FIG. 5.
